(57) **CLAIM**

The ornamental design for a robotic arm assembly, as shown and described.

DESCRIPTION

FIG. 1 is a front perspective view of a robotic arm assembly according to the new design.

FIG. 2 is a back perspective view thereof.

FIG. 3 is a side perspective view thereof.

FIG. 4 is a side perspective view thereof.

FIG. 5 is a top perspective view thereof.

FIG. 6 is a bottom perspective view thereof.

FIG. 7 is a front elevation view thereof.

FIG. 8 is a back elevation view thereof.

FIG. 9 is a side elevation view thereof.

FIG. 10 is a side elevation view, rotated 90° to the left, thereof.

FIG. 11 is a top plan view of FIG. 1; and,

FIG. 12 is a bottom plan view of FIG. 1.

Dotted lines in the drawings are portions of the robot arm assembly which form no part of the claimed design.
